SECTIONAL STEAM BOILER

William G. Cartter, Monrovia, Calif.

Application March 27, 1937, Serial No. 133,397

3 Claims. (Cl. 122—271)

This invention relates to a steam boiler, or the like, and particularly pertains to a sectional steam boiler.

The present invention contemplates the provision of steam boiler sections which are assembled as rigid units and may be installed within the boiler structure or separately removed as a unit without dismantling the entire boiler, and without in any wise disturbing the other units, the said sections comprising upper and lower tubular elements connected by intermediate tubes and flues of particular construction and design whereby a maximum heat exchange will take place in the structure.

15 The invention is illustrated by way of example in the accompanying drawings in which:

Figure 1 is a view in vertical section with parts in elevation showing the assembled structure with its outer housing and a unit positioned 20 therein with relation to the fuel burners.

Fig. 2 is an enlarged plan view of one of the burner elements with which the present invention is concerned, a portion being broken away to show a support for the baffle plates.

25 Fig. 3 is a view in horizontal section and elevation as seen on the line 3—3 of Fig. 1, showing the boiler structure and disclosing the assembled relationship of the various boiler units.

Fig. 4 is a view in central vertical section 30 through one of the boiler units as seen on the line 4—4 of Fig. 1 and particularly disclosing the wall configuration of the heat tube whereby a maximum exchange of heat may be produced.

Fig. 5 is a view in side elevation of another 35 form of the invention showing how the structure may be used as a radiating or cooling unit.

Fig. 6 is an end view of the structure as shown in Fig. 5 and showing an air blower.

Referring more particularly to the drawings, 40 the boiler comprises a base 10 upon which opposite vertical side walls 11 and 12 are disposed. An end wall 13 is positioned at one end of the base and a section wall 14 is disposed near the opposite end of the structure. These walls are 45 all preferably constructed of heat insulating material suitably enclosed by plates so to prevent the loss of heat by radiation and to conserve the heat within the furnace chamber 15. An end wall in the form of a plate 16 closes the 50 space between the ends of the side wall members 11 and 12. Spaces 17 and 18 are provided between the lower edges of the wall members 13 and 14 and the base 10, thus permitting an inflow of atmospheric air to the furnace chamber 15. A wall section 19 closes the upper end

of the furnace chamber 15 and is also constructed of heat insulating material. Mounted upon the base 10 are angle corner posts 20 between which vertical side wall elements 21 and 22 and end wall elements 23 and 24 are positioned. These elements are preferably of sheet metal. Spaced at intervals between the side wall elements 21 and 22 are intermediate partition walls 25 which form boiler unit spaces 26. Disposed in each of these spaces is a boiler unit 27. These comprise a lower manifold 28 and an upper manifold 29 and a plurality of intermediate columns 30. The upper and lower manifolds and their columns are preferably made of metal which has proper heat resisting qualities. These elements are preferably welded together and made of tubular stock. The manifolds 28 and 29 are provided with end domes 31 and 32 which close the ends thereof. These domes are formed with bracket arms 33 which 15 rest upon horizontal supporting elements 34 carried by the upright corner members 20. The domes 31 are each formed with a pipe connection 35. The pipe connection 35 of the lower dome connects with a water pipe 36, and the pipe 20 connection 35 of the upper dome connects with a water pipe 37. The pipes 36 of each of the units connect with a lower water manifold 38 and the pipes 37 of each of the units connect with an upper manifold 39. These manifolds 25 are cross-connected by a pipe 40 and are provided with a water supply pipe 41 here shown as directly connecting with the lower manifold 38. At a point intermediate the length of the pipe 40 a valve 42 is provided to control the flow 30 of water to the manifolds. Disposed centrally of each of the columns 30 is a tubular flue element 43. The construction of these elements is more particularly disclosed in Fig. 4 of the 35 drawings where it will be seen that they are essentially circular in cross-section and have alternate staggered concaved portions forming baffles 44. These baffles perform the function of causing the air heated by the burners 45 to pursue a sinuous course of travel upwardly 40 through the tubes so as to impart a maximum heat thereto. At the same time the water and steam passing upwardly through the tubular columns 30 in the space 46 between the flues 43 and the tubes 30 will be caused to circulate in 45 the convexed areas 44' which are provided exteriorly of the flue elements resultant of forming the baffles 44, and will insure a desired efficient exchange of heat between the gases 50 passing through the tubes and the water and 55

steam passing along the outside of the tubes and through the columns 30. The upper ends of the tubes 43 pass diametrically through the manifold 29 and communicate with a flue space 47 which leads to a flue box 48 from which a flue outlet 49 leads. Each of the boiler units as described are separately connected to the manifolds 38 and 39 by their pipes 36 and 37 through the medium of pipe unions 50. Thus it is possible to separate each of the heat exchange units from the manifold and remove it bodily without disturbing the rest of the units in the boiler.

The preferred form of heat supply for the structure here disclosed is indicated as a plurality of separate burner structures 45. These burner structures have vertical pipes 51 which are preferably attached to fuel supply pipes and a control valve not illustrated. The burner pipes are arranged uniformly over the area of the furnace and at the bottom thereof. At the upper end of each of said pipes a single burner jet 52 is mounted. The feature of the present invention by which high efficiency is obtained is concerned with the flow and distribution of air through the apparatus. False floors 53 and 54 are built above the main floor 55 of the furnace and are horizontally spaced therefrom. The space between the floors is divided into a plurality of passageways 56 by wall elements 57. Air may flow longitudinally 20 through the passageways 56 and upwardly around the ends of the floor and through openings 58 in the floors 53 and 54. These openings are of relatively large diameter as compared with the burner pipes 51 which extend through them. It will also be noted that an inflow of air is afforded through the throats 17 and 18 beneath the side walls of the structure, and that this air may flow upwardly to support combustion. Attention is directed to the fact that the columns 39 will be 30 exteriorly heated by the air flowing upwardly through the device since the air and products of combustion which do not pass through the tubes 43 will pass upwardly between the vertical partition plates 25 and around the columns. In order to insure intimate contact between the surface of the columns and this upwardly flowing air a plurality of inclined baffle plates 59 are provided and mounted on the inner sides of the partition plates 25. These baffle plates have cutaway portions 60 which conform to the outer surface of the columns 33 and embrace substantially one-half of their diameter. Thus with the plates being alternately arranged the air flowing upwardly between the vertical plates 25 will be caused to 40 follow a sinuous path of travel into the upper portion 47 of the boiler housing.

Referring more particularly to Figs. 5 and 6 of the drawings the structure which is there shown is designed to be used to furnish a radiating or cooling surface such as required in heating or cooling air for a building. This unit has a base 63 upon which opposite vertical angle posts 64 are mounted. Between these parts vertical side wall elements 65 and end wall elements 66 are positioned. Enclosed by these walls are boiler units 67. Each of the boiler units comprise a lower manifold 68 and an upper manifold 69 having end domes 71 and 72 and a plurality of intermediate columns 70. A pipe 73 connects the lower manifold 68 with a water pipe 74, and a pipe connection 75 connects the upper manifold 69 with a water pipe 75. The pipes 74 of each of the units connect with a lower water manifold 76 and the pipes 75 of each of the units connect with an upper manifold 78. These manifolds are cross

connected by a pipe 76 and are provided with a water supply pipe 77 here shown as directly connecting with the lower manifold 78. At a point intermediate the length of the pipe 76 a valve 80 is provided to control the flow of water to the manifolds. Disposed centrally of the columns 67 is a tubular flue element 81. The upper ends of the tubes 81 pass diametrically through the manifold 69. Carried above the flues 81 is a hood 82 from which a flue outlet 83 leads. Each of the boiler units, as described are separately connected to the manifolds 78 and 79 by pipes 74 and 75 through the medium of pipe unions 84. The unions 84 each connect the pipes 74 and 75 with the manifolds 78 and 79 which latter has a pipe leading from the unit to pipes 86 and 87. In the pipe 87 is a valve 88 which is operable to divert the water either to pipe 86 which carries hot water when the unit is used for heating, and to pipe 87 carrying off cold water when used for 20 cooling.

The heat supply for the structure here disclosed is indicated the same as in Figs. 1 and 2 comprising a plurality of separate burner structures 39, having vertical pipes 90 attached to a supply pipe and control valve not illustrated. The heat is confined to ascending only by way of the flues 31 as plates 91 and 92 close off the section containing the manifolds 58 and 69 and communicating columns 70. The intermediate 30 columns 70 have a series of baffle rings 93 upon them to retard the passage of air through the sections. As indicated at 94, the rings 93 are shown as overlapping the rings on adjacent columns so that the air as it travels upwardly may be completely conditioned as to heating or cooling. As shown in Fig. 6 a blower 95 of simple construction is provided having a base portion 96 and an air circulation portion 97 containing a fan blade 98 which may be used if desired to blow air against 40 plates 65.

In operation of the present invention the boiler is assembled as shown in Figs. 1 and 3 of the drawings. When assembled the various units 27 are connected with the headers 38 and 39 by the pipes 36 and 37 and the unions 50. The various burners are suitably connected with a fuel supply pipe and when the fuel is ignited the burners will produce a flame which passes upwardly to impinge against the lower manifolds 28. A desired proportion of the products of combustion will pass through the tubes 43. Water will be delivered to the lower end of the boiler section through the water supply pipe 41 and the manifold 38 and will then pass through all of the pipes 36 to the lower manifolds 28 of each of the units. The atmospheric air entering through the passageways 17 and 18 under walls 13 and 14 will flow upwardly and pass around and between the columns 39 of the individual boiler units. This air will be deflected by the inclined baffle plates 53 disclosed in Fig. 4 and will pass outwardly through the flue 49. The steam or hot water will pass from the units through the pipes 27 into the header 39 and may then pass through a pipe 82 to a suitable point of use. When it is necessary or desirable to remove one of the heat units 27 its particular pipes 36 and 37 may be disconnected from the headers 38 and 39, after which the unit will be completely separated from the rest of the structure and may be lifted from its seated position upon the supporting members 34. It will thus be seen that the only necessary points of attachment are the pipes 36 and 37. Attention is also directed to the fact that the units are made 70

of suitable non-cracking heat resisting material which makes it possible for them to be light in weight, relatively small in compass and of great durability.

5 In operation of the present invention as is seen assembled in Figs. 5 and 6 of the drawings various uses may be made of the apparatus as the operator may desire. When assembled as seen in Figs. 5 and 6 of the drawings the apparatus may be used as a boiler for producing steam or hot water. The structure may also be used to heat or cool air or to condition the same. If when being used as a boiler the blower 95 is operated the air taken off of the opposite side will be hot and may be piped to various parts of the building. If it is desired to cool air the heating elements 89 may be shut off and the blower 95 will be blowing air against the unit containing cold water, which can be then taken away by piping means to cool the temperature of a building.

20 While I have shown the preferred form of my invention, as now known to me, it will be understood that various changes might be made in the combination, construction, and arrangement of parts, by those skilled in the art, without departing from the spirit of the invention as claimed.

Having thus described my invention, what I claim and desire to secure by Letters Patent is:

1. In a sectional boiler, a boiler unit comprising upper and lower horizontal manifolds, vertical columns establishing communication therebetween and being formed integral therewith, flue tubes extending longitudinally through said columns and transversely across said manifolds and being formed integral therewith, said tubes being open at their opposite ends to conduct a flow of gas through the boiler unit, means for supporting and enclosing a plurality of said boiler units, said means including vertical partition members positioned between said units whereby separate air passages will be formed for each unit, inclined baffle plates mounted on the inner surface of said vertical partition members embracing substantially one-half the diameter

of the vertical columns whereby a sinuous path of travel of the air will be created.

2. In a sectional boiler, a boiler unit comprising upper and lower horizontal manifolds, vertical columns establishing communication between said manifolds and being formed integral therewith, flue tubes extending longitudinally through said columns and transversely across the manifolds and being formed integral therewith, said tubes being open at their opposite ends to 10 conduct a flow of gas through the boiler unit, said flue tubes being formed with a series of concave portions on their outer face forming baffles whereby the heat exchange surface will be increased, means for supporting and enclosing a plurality of said boiler units, said means including vertical partition members positioned between said units whereby separate air passages will be formed for each of said units. 15

3. In a sectional boiler, a boiler frame for supporting and enclosing a plurality of boiler units, a series of burners in the lower portion of said frame, said boiler units comprising upper and lower horizontal manifolds positioned above said burners, vertical columns establishing communication therebetween and being formed integral therewith, flue tubes extending longitudinally through said columns and transversely across said manifolds and being formed integral therewith, said tubes being open at their opposite ends to conduct the flow of gas through the boiler units, said tubes being formed with a series of concave portions on their surface providing baffles whereby the heat exchange surface will be increased and the upwardly moving gas from the burners will follow a sinuous path of travel, said boiler frame carrying vertical partition members positioned between said units whereby separate air passages will be formed for each of said units, said partitions comprising a plurality of inclined baffle plates having cutaway portions conforming to the outer surface of the vertical columns and embracing substantially one-half of their diameter whereby the air flowing upwardly between the vertical plates will follow a 30 sinuous path of travel. 35

WILLIAM G. CARTTER.
